(57) CLAIM

The ornamental design for a sports hat as shown and described.

DESCRIPTION

FIG. 1 is a front view of the sports hat;

FIG. 2 is a top view thereof;

FIG. 3 is a side view thereof; and,

FIG. 4 is a side perspective view thereof.

The broken lines of the sports hat depict portions of the sports hat that form no part of the claimed design.

1 Claim, 4 Drawing Sheets
